UNITED STATES PATENT OFFICE.

HENRY SINGLETON GRIESBACH, OF CHISWICK, ENGLAND.

VAPORIZER FOR INTERNAL-COMBUSTION ENGINES.

1,142,090.

Specification of Letters Patent. Patented June 8, 1915.

Application filed November 17, 1911. Serial No. 660,874.

To all whom it may concern:

Be it known that I, HENRY SINGLETON GRIESBACH, subject of the King of Great Britain, residing at 18 Riverview Grove, Chiswick, Middlesex, England, have invented certain new and useful Improvements in Vaporizers for Internal-Combustion Engines, of which the following is a specification.

10 This invention relates to internal combustion engines and particularly to arrangements employed in connection therewith for producing the necessary vaporized condition of the liquid hydrocarbon fuel employed.

It is frequently desirable that engines of the above character be operated either with light hydrocarbon fuel, such as petrol, or heavier hydrocarbon fuel such as petroleum or paraffin, in accordance with varying conditions, and the present invention has for its object to devise improved vaporizing arrangements for the heavier fuel which can be fitted to internal combustion engines adapted for use with lighter fuel without any substantial structural alteration in the design of the engine, at the same time enabling the engine to be operated under the most efficient conditions as regards compression regardless of whether the engine is being supplied with heavy or light fuel.

Internal combustion engines adapted to be operated by liquid fuels of different character as regards the degree of temperature required to effect volatilization and otherwise are now well known in the art, but it is found in practice difficult to transform an engine constructed for use with one fuel in such a manner as to render it capable of being operated by a different fuel without a considerable alteration in the general design and construction of the engine, and, furthermore, the greater temperature required to vaporize heavy hydrocarbon fuel, such as petroleum, as compared with lighter fuels, such as petrol, render those engines in which the heat necessary for the vaporization of the heavy fuel is obtained from the exhaust gases of the engine as is usual inefficient and unsatisfactory in operation.

According to the present invention the vaporizing device employed when the engine is operated by heavy fuel is so located as to obtain the heat necessary for vaporization directly from the cylinder or combustion chamber of the engine and to thereby

utilize the high temperature existing in the latter.

A further feature of the invention consists in the special arrangement and construction of the vaporizing device which comprises essentially a tubular member located within a portion of the combustion space of the cylinder, the tubular member constituting a conduit through which the heavy liquid fuel passes on its way to the cylinder or cylinders of the engine. By so proportioning and locating the tubular vaporizing member the passage of the combustible liquid therethrough may be utilized to reduce the temperature existing in that portion of the combustion space of the cylinder in which the tubular member is located by transferring the heat from the interior of the combustion space to the liquid fuel through the walls of the tubular member. By this means not only is the heat in the combustion chamber utilized for vaporization purposes but the withdrawal of heat from the combustion space serves to maintain the latter at a lower temperature than would otherwise obtain in this space, thereby enabling a higher degree of compression to be employed in the cylinder without risk of pre-ignition. The vaporizer is also so constructed and attached to the cylinder of the engine as to provide the necessary increase in the volume of the compression space when heavy fuel is employed, and the vaporizer can readily be attached to a standard type of engine.

In order that the nature of the invention may be clearly understood it will now be described with reference to the accompanying drawings, of which—

Figure 1 is a view in front elevation partly diagrammatic illustrating a four-cylinder internal combustion engine provided with one form of vaporizing apparatus constructed in accordance with the invention. Fig. 2 is a sectional view illustrating on an enlarged scale the construction of a single vaporizer of the engine shown in Fig. 1; Fig. 3 being a view in sectional elevation on the line III—III of Fig. 2. Fig. 4 is a view similar to Fig. 3 illustrating a modified form of vaporizer which may be employed. Fig. 5 is a fragmental view of a portion of the engine showing the vaporizer illustrated in Fig. 4 mounted in position; Fig. 6 a view similar to Figs. 3 and 4 illustrating a further modification in which

means are provided for cooling the vaporizer by means of a water jacket. Figs. 7 and 8 are views in plan and elevation respectively, partly sectional, illustrating a modified form of vaporizer embodying the invention. Fig. 9 is a view similar to Fig. 5 showing a vaporizer of the same general construction but provided with modified means of attachment to the cylinder of the engine, Fig. 10 being a sectional view on the line X-X of Fig. 9. Fig. 11 is a view similar to Fig. 1 but illustrating partly in section a further modification in which all the vaporizers of the engine are arranged to be cooled by a common water jacket.

Referring now to Figs. 1 and 2, the internal combustion engine comprises four cylinders indicated at 1, 2, 3, 4 the inlet ports of which are connected to a common induction pipe 5. The latter is connected through an air valve 6 of any suitable type to a pipe 7 leading to the last of a number of vaporizers 8, 9, 10, 11, each of which is mounted on the top of one of the cylinders 25 of the engine. The vaporizers 8, 9, 10, 11 are connected in series with one another to a carburetor 12 through a regulating valve 13. The construction and location of each of the vaporizers will be more readily understood from a reference to Figs. 2 and 3 of the drawings, in which the vaporizer is indicated as comprising an outer casing 14 having ribs 15 on its external surface for the purpose of radiating heat. The casing 14 is provided with a nipple 16 which is screwed into a threaded plug or cap at the top of the cylinder, so that the interior 17 of the casing 14 is in free communication with its corresponding cylinder and forms a 40 portion of the combustion chamber of the engine. A tube 18 having thin walls of copper or other suitable material passes through the interior of the casing 14 and is continued through the casings of all the 45 vaporizers of the engine as shown in Fig. 1. One side of each of the casings 14 is provided with a hole 19 in which a sparking plug or other ignition device (not shown in the drawings) is secured. The operation of 50 this form of the apparatus is as follows:— The mixture comprising atomized petroleum and air drawn through the regulating valve 13 during the suction stroke of the engine passes through the pipe 18 which is surrounded by the vaporizer casings. The 55 petroleum is vaporized by the heat due to the explosions in the several cylinders and after leaving the last vaporizer 11 passes through the air valve 6 where it is mixed 60 with a suitable proportion of atmospheric air finally passing to the cylinders through the inlet ports. The construction of the vaporizers is such that, as will be readily seen from the drawings, the nipple of each vaporizer is screwed into the hole usually oc-

cupied by the sparking plug when the engine is intended to operate with petrol or other light hydrocarbon fuel, and an engine normally constructed for operation with petrol may thus be readily converted for use 70 with heavy hydrocarbon fuels by removing the sparking plugs and replacing these by the vaporizer casings. The space within the interior of the latter constitutes as above stated a portion of the combustion chamber 75 of each cylinder and the increased compression space thus provided serves to secure a high efficiency when the engine is operated with petroleum.

The tubular vaporizing member is of such 80 dimensions and is so located relative to the walls of the vaporizing chamber in which it is located that the thickness of the layer of combustible mixture by which it is surrounded is substantially uniform, so that the 85 whole of the vaporizer casing will be maintained at a substantially uniform temperature which, as above stated, is below that required for ignition at the degree of compression which is obtained. Owing to the 90 uniformity in the cross-sectional area of the space separating the tubular vaporizer member and the vaporizer chamber surrounding it, local overheating of any portion of the chamber is prevented and a frequent cause 95 of pre-ignition thereby avoided.

It will be apparent that a substantially constant vaporization will be obtained in operation due to the fact that the mixture of atomized petroleum and air drawn in 100 through the regulating valve must of necessity be subjected to the maximum temperature obtaining in one or other of the four cylinders.

In the construction shown in Figs. 1, 2 105 and 3 the vertical height of the engine is somewhat increased by the addition of the vaporizers and in cases where this is undesirable the vaporizer casings may be constructed as shown in Figs. 4 and 5 in which 110 it will be seen that the vertical height of the engine is only very slightly increased by the addition of the vaporizers since the portion of the vaporizer surrounding the tube 18 is on one side or the other of the nipple 115 16 instead of being vertically above the latter.

In some cases it may be desirable to employ water cooling jackets for the vaporizers in which case the form of vaporizer illustrated in Fig. 6 may be employed. In this construction a space for the cooling water is provided with inlet and outlet ports 20, 21 respectively.

Referring now to Figs. 7 and 8, a modified form of the invention is illustrated, in which instead of attaching each of the vaporizers separately to the corresponding cylinders of the engine when it is desired to operate the latter with heavy hydrocarbon 125 180

fuel a special cover is provided which contains the vaporizer casings for all the cylinders of the engine and which replaces the cover ordinarily employed when operating the engine with lighter fuel. The construction shown in Figs. 7 and 8 is suitable for use with a two-cylinder engine and comprises a casting 22 containing two vaporizer chambers 23, 24 which communicate with the cylinders of the engine by means of exteriorly threaded tubular members 25, 26 projecting through the base of the casting 22 and being adapted to maintain the same in efficient relation to the cylinder by means of nuts 27, the base of the casting adjacent to the tubular members being provided with ground or machined surfaces for the purpose of insuring a tight joint. The vaporizing tubes 18 are arranged transversely across the casting with the vaporizing chambers and are connected to one another in any suitable manner so that the mixture of petroleum or other heavy hydrocarbon fuel and air passes through the vaporizing tubes simultaneously or successively prior to being further diluted with air and admitted to the cylinders of the engine.

Referring now to Figs. 9 and 10, a modified construction is illustrated in which the nipples 16 of the vaporizers are provided with externally coned surfaces adapted to enter corresponding internally coned surfaces in plugs or bushings 28 fitted to the top of the cylinder, the vaporizers being held in place by a forked clamping member 29, the lower ends of which engage with pins 30 on the plugs 28, the upper part of each clamping member 29 being provided with screws 31 by means of which the coned surfaces on the vaporizer nipple 16 and the plug 28 may be held firmly in contact with one another.

As will be readily understood by the use of this construction the vaporizers can be readily and quickly removed when necessary by loosening the screws 31 and removing the clamping members 29, whereupon the plugs 28 may be unscrewed and replaced by the usual plugs.

Referring now to Fig. 11, a further modification is illustrated in which all the vaporizers of the engine are surrounded by a casing 32 supplied with cooling water in any suitable manner, the inlet ports to each of the cylinders of the engine being in this case located within a cylinder casing surrounding all the cylinders.

In order to avoid the necessity of detaching and removing the vaporizers from the engine when it is intended to operate the latter by means of light hydrocarbon fuel after it has been operating with a heavier fuel,

the present invention contemplates the provision of plug cocks or other controlling valves interposed between each or all of the vaporizers and the engine cylinders so as to permit communication between the latter and the interior of the vaporizing chambers to be cut off when desired, it being understood that the sparking plugs are in this case located on the cylinder side of the plug cocks or valves.

It will be understood that the invention is not limited to any particular type of regulating mechanism for controlling the amount or richness of the mixture supplied to the vaporizers or to the engine, for instance, instead of regulating the amount of air admitted to the vaporizer by hand, automatic means such as a spring-controlled valve adapted to vary the amount of air admitted to the engine either in accordance with its speed or with the degree of suction may be provided. Moreover it will be apparent that the invention is not limited to the particular construction described for the vaporizer or to its location and various modifications may be made without exceeding the scope of the invention.

What I claim is:—

1. In combination with an internal combustion engine, a detachable cylindrical vaporizer having a spark plug aperture formed therein, a thin tubular member extending coaxially through said vaporizer, and a nipple formed on the vaporizer adapted to be screwed into the spark plug opening of the engine cylinder.

2. In combination with the cylinders of a multi-cylinder internal combustion engine, a separate casing detachably secured to each cylinder of the engine with its interior communicating with the interior of the engine cylinder, and a vaporizer tube passing through all of said casings and exposed between adjacent casings.

3. In combination with the separate cylinders of a multi-cylinder internal combustion engine, separate casings detachably secured to each cylinder with the interior of each casing communicating with the interior of the engine cylinder on which it is mounted, a water jacket for all of said casings, a vaporizer tube passing through all of said casings and exposed to the temperature of the water jacket between adjacent casings.

In testimony whereof I have hereunto set my hand in presence of two subscribing witnesses.

HENRY SINGLETON GRIESBACH.
